HOIST HOOK

Perry L. Dukes, Coulee Dam, Wash., assignor to Bacon-Dukes, Inc., Ephrata, Wash., a corporation of Washington

Filed June 27, 1962, Ser. No. 295,624
4 Claims. (Cl. 294—83)

The present invention relates to a hoist hook such as one used for elevating a cement hopper or bucket for pouring of cement.

An object of the present invention is to provide a hoist hook which has instant release means which enables the operator of the hoist to engage the bail of a cement bucket, raise the cement bucket and empty it at the desired location, return the bucket to the ground level, and disengage the hoist hook in a single operation.

Another object of the present invention is to provide a hoist hook for engaging the bails or attaching elements of any number of articles, one which is automatic in operation, one simple in structure, one sturdy in construction, and one which is highly effective in action.

A further object of the present invention is to provide a hoist hook which may be manufactured at a reasonable cost, one which is foolproof in operation, one which, when engaging the bail of a cement bucket or the like, cannot be released without returning the cement bucket to the ground level.

These and other objects and advantages of the present invention will become apparent from the following description when taken in connection with the annexed drawings, in which:

FIGURE 1 is a side elevational view of the hoist hook of the present invention with one of the side plates removed therefrom, the hook being shown in position prior to receiving the bail of a bucket.

FIGURE 2 is a view similar to FIGURE 1 showing the bail of the bucket received in the throat of the hook.

FIGURE 3 is a view similar to FIGURES 1 and 2 showing the bail in a hoist position.

FIGURE 4 is an end elevational view.

FIGURE 5 is a view taken on the line 5—5 of FIGURE 3.

FIGURE 6 is a view taken on the line 6—6 of FIGURE 3.

FIGURE 7 is a view taken on the line 7—7 of FIGURE 3, and

FIGURE 8 is a view taken on the line 8—8 of FIGURE 2.

With reference to the drawings in detail, and in which like numerals indicate like parts throughout the several views, the hoist hook of the present invention comprises a pair of vertically disposed plates 10 and 12 arranged in face to face spaced relation. In FIGURES 1, 2, and 3, the plate 10 has been removed to show the inside of the hoist hook of the present invention.

Registering holes 16 are formed in the upper ends of the plates 10 and 12 for the reception therethrough of an end link 14 of a chain hoist.

The plates 10 and 12 are secured together by vertically extending side plates 18 and 20, a top plate 22, and bottom plates 24 and 26.

The plates 10 and 12 are provided with registering slots 28 and 30, respectively, with the slots 28 and 30 extending from the lower ends of the plates 10 and 12 and terminating at a point spaced from the upper ends of the plates 10 and 12.

The slots 28 and 30 form a vertically disposed throat for receiving therein the bail 32 of a cement bucket or the like.

Also connecting the plates 10 and 12 together are channel members 34 and 36 forming the guide way for

2

the bail 32. Extending between the plates 10 and 12 and having its ends secured thereto is a support bar 38 positioned on one side of the throat and adjacent the lower end part of the throat.

5 A latch 40 is supported upon a horizontally disposed pin 24 which has its ends anchored in the plates 10 and 12, as shown in FIGURE 6, the latch 40 being movable about the pin 42 as a horizontal axis from a position in which the portion adjacent one end rests upon the support bar 38 and bridges the throat formed by the slots 28 and 30 to a position in which, as shown in FIGURE 1, the one end portion is in non-bridging relation with respect to the throat.

The latch 40 is normally in the position shown in FIGURE 1 and means is provided by the present invention operatively connected to the latch 40 and engageable with the bail 32 when the bail 32 is wholly received in the throat to shift the latch 40 from the normal position of FIGURE 1 to the bridging position of FIGURE 2 and of FIGURE 3 for a support of the bail 32 on the latch 40 as in FIGURE 3.

20 Specifically, this means consists in an arm 44 extending over the upper end of the throat and having one end pivotally connected by a pin 46 to the plates 10 and 12 for swinging upward and downward movement of the arm 44 between the positions shown in FIGURES 1 and 2.

25 Means is provided by the present invention operatively connected to the latch 40 for holding the latch 40 in the position shown in FIGURE 2 bridging the throat formed by the slots 28 and 30. Specifically, this means 30 comprises a lost motion connection 48 consisting in an upper shank 50 and a lower bar 52 having its upper end provided with a bore 54 receiving the shank 50.

The upper end of the shank 50 is pivotally connected 35 by a pin 56 to the end of the arm 44 remote from the pin 46.

The bar 52 is bifurcated for one-half of its length, the lower half, and the end of the bifurcation at the upper end provides a shoulder 58 against which a nut 60 on the shank 50 bears when the shank is in its uppermost position with respect to the bar 52, as shown in FIGURE 2.

30 The bifurcated lower end of the bar 52 is connected by a pin 62 to the portion of the latch 40 remote from the support bar 38, so that the lost motion connection 48 executes upward and downward movement to responsive to rocking or swinging movement of the latch 40 about the pin 42 as an axis.

35 The means for holding the latch in the bridging position also includes a pin 64 extending through the arm 44 and engageable with a ledge or hook 66 provided in the intermediate portion of an upright keeper 68 which has its upper end pivotally connected by a pin 70 to the plates 10 and 12.

40 Means is also provided for dislodging the keeper 68 from the pin 64 so that the latch 40 may return from the position shown in FIGURE 3 bridging the throat of the hook to the position shown in FIGURE 1 in which the latch 40 is in the non-bridging position free of the throat. Specifically, this means includes a sloping face 72 on the lower end of the keeper 76, the face 72 being engageable by a cam ledge 74 carried on the upper end of the bar 52.

45 A roller 76 is journaled on the underside of the arm 44 intermediate the ends thereof and is adapted to engage the upper face of the bail 32 when the latter is inserted into the throat formed by the slots 28 and 30.

50 A bolt 78 has one end pivotally connected to the plates 10 and 12 and has a spring 80 circumposed about the portion of the bolt 78 between the keeper 68 and a nut and washer assembly 82 on the bolt 78. The spring 80 serves to bias the keeper 68 to the position in which the

pin 64 would be received in the hook 66 if the arm 44 is in the upward position as in FIGURE 2.

In operation, the hook of the present invention is lowered by the chain links 14 to a position in which the bail 32 of a cement bucket or other article is directly below the slots 28 and 30. The sloping faces of the bottom plates 24 and 26 serve to guide the bail 32 into the throat formed by the slots 28 and 30. Upon lowering of the hook from the position shown in FIGURE 1 to the position shown in FIGURE 2, the bail 32 engages the roller 76 and raises the arm 44 to the position shown in FIGURE 2 at which time the spring 80 urges the keeper 68 to the right in FIGURE 2 so that the hook 66 engages the pin 64.

The shank 50 of the lost motion connection 48 is at its extended position with respect to the bar 52 and the latch 40 is in the position shown in FIGURE 2 midway between the normal position of FIGURE 1 and the bridging position of FIGURE 3. Now upon raising of the hook the bail 32 travels relatively downwardly of the throat to engage the top of the latch 40 and to force it to the position shown in FIGURE 3, at which time the hook may be raised carrying the bail and bucket with it.

In the position of the elements shown in FIGURE 3, the action of the bail 32 on latch 40 raises bar 52 and urges cam ledge 74 against face 72 and shifts keeper 68 to the left freeing pin 64 from hook 66. Arm 44 is then allowed to drop in a downward direction to the position shown in FIGURE 1. The latch 40 is free to rotate under the action of gravity. The combined weight of the arm 44, bar 52 and the right hand portion of the latch 40 exceeds the weight of the left hand portion of the latch 40. This results in the latch 40 swinging to the non-bridging position shown in FIGURE 1 permitting the hook to be raised from the bail 32.

While only preferred embodiment of the present invention is shown and described, other embodiments are contemplated and numerous changes and modifications may be made therein without departing from the spirit of the invention, as set forth in the appended claims.

To release the bucket from the hook, the operator of the crane merely has to lower the bucket to ground level or a similar supporting surface.

The bail 32 begins to move up within the vertically disposed throat far enough to clear the latch 40 so that the latter may rotate in a clockwise position as shown in FIGURE 1.

Should the bail 32 move upwardly too far and engage the roller 76 on the arm 44 the hoist hook mechanism will then be reset or cocked and in order to release the bail from the throat and move the latch 40 into the position shown in FIGURE 1, it will be necessary that the bail 32 be brought into engagement with the latch 40 to occupy the FIGURE 3 position and then repeat the releasing cycle and by being cautious not to engage the roller 76.

What is claimed is:

1. A hook for a hoist comprising a pair of vertically disposed plates arranged in face to face spaced relation, there being a vertically disposed slot in each plate extending from the lower end thereof and terminating at a point spaced from the upper end of said plate, said slots being in registry with each other and together providing a throat to receive therein the bail of an article to be hoisted, a support bar extending between and connected to said plates adjacent to and on one side of said throat and inwardly of the lower end of said throat, a latch disposed on the other side of said throat opposite to said support bar and normally having the portion adjacent one end spaced above said support bar and in non-bridging relation with respect to said throat, said latch having its mid-portion connected to said plates for pivotal movement from the normal position to a position with said one end portion resting upon said support bar and bridging said throat, said latch being movable by the force of gravity from the bridging position to the normal position, means

operatively connected to said latch and engageable with a bail when said bail is wholly received in said throat to shift said latch from the normal position to the bridging position for supporting said bail on said latch, and means operatively connected to said latch for releasably holding said latch in the bridging position.

2. A hook for a hoist comprising a pair of vertically disposed plates arranged in face to face relation, there being a vertically disposed slot in each plate extending from the lower end thereof and terminating at a point spaced from the upper end of said plate, said slots being in registry with each other and together providing a throat to receive therein the bail of an article to be hoisted, a support bar extending between and connected to said plates adjacent to and on one side of said throat and inwardly of the lower end of said throat, a latch disposed on the other side of said throat opposite to said support bar and normally having the portion adjacent one end spaced above said support bar and in non-bridging relation with respect to said throat, said latch having its mid-portion connected to said plates for pivotal movement from the normal position to a position with said one end portion resting upon said support bar and bridging said throat, said latch being movable by the force of gravity from the bridging position to the normal position, means operatively connected to said latch and engageable with a bail when said bail is wholly received in said throat to shift said latch from the normal position to the bridging position for supporting said bail on said latch, and means operatively connected to said latch for releasably holding said latch in the bridging position, and other means operatively connected to the last mentioned means for effecting the release of said latch upon partially receiving said bail in said throat.

3. A hook for a hoist comprising a pair of vertically disposed plates arranged in face to face spaced relation, there being a vertically disposed slot in each plate extending from the lower end thereof and terminating at a point spaced from the upper end of said plate, said slots being in registry with each other and together providing a throat to receive therein the bail of an article to be hoisted, a support bar extending between and connected to said plates adjacent to and on one side of said throat and inwardly of the lower end of said throat, a latch disposed on the other side of said throat opposite to said support bar and normally having the portion adjacent one end spaced above said support bar and in non-bridging relation with respect to said throat, said latch having its mid-portion connected to said plates for pivotal movement from the normal position to a position with said one end portion resting upon said support bar and bridging said throat, said latch being movable by the force of gravity from the bridging position to the normal position, an arm extending over the upper end of said throat and having one end pivotally connected to said plates for swinging upward and downward movement of said arm, a link having one end pivotally connected to the other end of said arm and having the other end pivotally connected to the other end of said latch for upward and downward movement with said latch other end responsive to movement of said latch, an upright keeper having the upper end pivotally connected to said plates for swinging movement about a horizontal axis, a pin extending through said arm adjacent said link and releasably engaging with said keeper responsive to downward movement of said arm, and means on said link engageable with said keeper responsive to upward movement of said link and operable to release said pin from said keeper.

4. A hook for a hoist comprising a pair of vertically disposed plates arranged in face to face relation, there being a vertically disposed slot in each plate extending from the lower end thereof and terminating at a point spaced from the upper end of said plate, said slots being in registry with each other, and together providing a

throat to receive therein the bail of an article to be hoisted, a support bar extending between and connected to said plates adjacent to and on one side of said throat and inwardly of the lower end of said throat, a latch disposed on the other side of said throat opposite to said support bar and normally having the portion adjacent one end spaced from said support bar and in non-bridging relation with respect to said throat, said latch having its mid-portion connected to said plates for pivotal movement from the normal position to a position with said one end portion resting upon said support bar and bridging said throat, said latch being movable by the force of gravity from the bridging position to the normal position, an arm extending over the upper end of said throat and having one end pivotally connected to said plates for swinging upward and downward movement of said arm, a lost motion link having one end pivotally con-

nected to the other end of said arm and having the other end pivotally connected to the other end of said latch for upward and downward movement with said latch other end responsive to movement of said latch, an upright keeper having the upper end pivotally connected to said plates for swinging movement about a horizontal axis, a pin extending through said arm adjacent said link and releasably engageable with said keeper responsive to downward movement of said arm, and means on said link engageable with said keeper responsive to upward movement of said link and operable to release said pin from said keeper.
